UNITED STATES PATENT OFFICE.

HARRY W. DENHARD, OF SAN FRANCISCO, CALIFORNIA, ASSIGNOR TO THE CUTLERY HAMMER MFG. CO., OF MILWAUKEE, WISCONSIN, A CORPORATION OF WISCONSIN.

ELECTRIC ATTACHMENT DEVICE.

1,169,532.

Specification of Letters Patent. Patented Jan. 25, 1916.

Application filed November 15, 1911. Serial No. 660,371.

To all whom it may concern:

Be it known that I, HARRY W. DENHARD, a citizen of the United States, residing at San Francisco, in the county of San Francisco and State of California, have invented new and useful Improvements in Electric Attachment Devices, of which the following is a full, clear, concise, and exact description, reference being had to the accompanying drawing, forming a part of this specification.

My invention relates to electric attachment devices.

It has among its objects to provide an improved electric attachment device.

A further object of my invention is to provide an improved electric attachment device which may be made up of a small number of parts in a very compact form, and in which the conducting members are of an improved construction.

A further object of my invention is to provide an improved electric attachment device which is especially adapted to be used in connection with electric heating or other devices and which may be readily attached to the device providing a suitable coöperating member for an attachment plug of any desired form.

Other objects and advantages of my improved construction will hereinafter appear.

In the accompanying drawings I have, for purposes of illustration, shown one form which my invention may assume in practice.

My invention is not, however, limited to this form but may assume other forms.

In the views of these drawings: Figure 1 shows a top plan view of one of the parts of the attachment device. Fig. 2 shows a top plan view of the same with one of the base members removed. Fig. 3 shows a side elevation of the parts shown in Fig. 1. Fig. 4 shows a longitudinal sectional view of the same. Fig. 5 shows a detail view of one of the base members of the same. Fig. 6 shows a perspective view of one of the contact members for the same.

In the construction shown I have illustrated an attachment plug having two base members 1 and 2, which are arranged to be fitted together, and carry between them electrical contact members. In a preferred form the base members 1 and 2 are formed of porcelain or molded stone. The base member 1 is preferably provided with a

stepped lower surface as shown in Fig. 3, a projection 4 being provided at its back and a projection 5 being provided at its forward end. These projections are arranged to fit snugly into corresponding recesses or steps 60 on the upper surface of the coöperating base member 2. In a preferred form the upper surface of the base member 1 is made substantially flat and lies substantially flush with the surface of an upwardly extending 65 portion of the base member 2, while the back of the base member 1 is rounded off as shown at 6 in Fig. 3, being adapted to form with the back of the member 2 upon which it rests, a substantially smooth curved surface. In a preferred form the forward surface of the member 2 is rounded as shown at 7, and the sides of the members 1 and 2 are preferably sloping, as shown in Fig. 1, the two parts being so constructed that they fit 75 snugly upon each other and provide a substantially smooth outer surface.

The contact members are preferably constructed as shown in Fig. 6. In a preferred form I provide a contact shank 8 of substantially rectangular cross-section, having an extension 9 substantially at right angles to it. A body member 10 having an upwardly extending projection 11 preferably formed integral with the same and extending at right angles thereto, is preferably swiveled as by a binding screw 12 to the extension 9 on the shank 8. In a preferred form the body member 10 is substantially flat throughout the greater portion of its 80 length and is provided with a depressed portion 13 at the end opposite the extension 11, in which depressed portion is suitably secured, as by a nut 14, a terminal plug 15 which may be of the usual construction. 85

The base members 1 and 2 are preferably provided with internal recesses arranged to receive two or more of the contact members. In a preferred form the contact members are made in what may be called right and left members, the body member 10 in the right member having its extension 11 on its left-hand side, while the body member 10 on the left-hand member has its extension 10 on its right-hand side. The shanks 8 105 preferably extend upward through suitable slots or recesses 16 in the two base members 1 and 2. In a preferred form the openings 16 are formed as registering slots in each of the base members. The body members 110

10 of the contact members are preferably seated in suitable recesses 17 in the base member 2, which communicate with the slots 16 by means of suitable recesses or 5 slots in which the extensions 9 are housed. In order to receive the depressed portion 13 of the contact members, slightly deeper recesses 18 are preferably provided at the back of the base 2, and in order that the 10 terminal plugs 15 may extend through the bottom of this base member suitable recesses or holes are provided on the opposite sides of the base. If desired, the base member 2 may be provided with suitable extensions or 15 nipples 19 arranged to protect the upper ends of the terminal plugs, these nipples being preferably formed integral with the base. The upper base member 1, in order that it may coöperate with the base 2 in receiving the contact members, is preferably provided with a plurality of recesses 20 arranged to house the swivel connection of the contact members. In a preferred form these recesses 20 communicate with the slots 16 20 through suitable recesses 21 arranged to house the extensions 9. If desired the two parts of the bases 1 and 2 may be attached together by any suitable means extending through a suitable recess 22 in the bodies 25 of the bases 1 and 2 between the contact members.

In applying my attachment device to a device carrying a switch mechanism, I preferably provide one of the base members 30 with a recess 23 leading to the contact members, which is preferably slightly enlarged in cross-section as it approaches the latter. The conductors for the switch mechanism are brought in through this recess and attached to one or more of the contact members, the removable section 10 being taken out by simply loosening the holding means at its ends. Where a single pole switch mechanism is used, for instance, the conductors may be attached to the binding screw 12 and the tap 14 on one of the contact members. As in the ordinary use of the device, the shanks 8 in this instance may be attached to a removable attachment plug, 35 and the plugs 15 inserted in the plugs on the heating unit, or vice versa.

It will thus be seen that an improved attachment or connecting device has been provided which may be readily taken apart and 40 in which new parts may be easily substituted since the contact members are so arranged that they may be removed as an entirety from the base. The attachment is made of a small number of parts of simple 45 construction which may be readily standardized and manufactured at small expense. The construction is especially adapted to be carried by an electric heater or other relatively small translating device in which a 50 switch member is used, since the attachment

may be readily connected to the switch mechanism. The construction is compact, the parts are effectually insulated and the whole attachment presents a neat appearance.

It should be understood that the structure shown is for purposes of illustration only and that other structures may be devised which embody the invention and which come within the spirit and scope of the appended claims.

What I claim as new and desire to secure by Letters Patent of the United States is:

1. An electric attachment device comprising an insulating base divided into two parts, a pair of offset plug connectors, each comprising two plug contacts extending in opposite directions in offset relation and connected together by a detachable member, said connectors being located in said base 80 so that the detachable connecting member is between the two sections of said base whereby when one section is removed the connecting member may be readily detached.

2. An electric attachment device comprising in combination, a sectional insulating base having a plurality of pairs of plug contacts protruding from opposite sides thereof in an offset relation and a removable conducting member between the sections of 90 said base for electrically connecting certain of said opposite contacts.

3. An electric attachment device comprising in combination, a sectional insulating base having pairs of plug contacts protruding from opposite sides thereof in offset relation and a pair of conducting members between the sections of said base for removably securing corresponding contacts of each of said pairs together, each pair of 100 said contacts being removable independently of the other pair.

4. An electrical connector comprising in combination, a sectional insulating base having clamped between the parts thereof a pair of contacts with extensions protruding from opposite sides of said base, and conducting means between the parts of said base for electrically connecting certain of said contacts together, each pair of 110 said contacts being removable independently of the other pair and said conducting means being removable independently of both pairs of said contacts.

5. An electrical connector comprising in combination, a divided insulating base, a pair of contacts clamped between the parts of said base and protruding from opposite sides thereof, terminal posts at the extremity of each of said contacts within said base 120 and conducting members removably secured to certain opposite contacts by said terminal posts, said base having an opening extending adjacent said terminal posts whereby 125 line wires may enter the same for attach- 130

ment to said terminal posts when said corresponding conducting member is removed.

6. An electric attachment device, comprising in combination, a divided insulating base, the parts thereof having complementary stepped adjacent faces, a pair of protruding contacts mounted in one part, a pair of oppositely protruding contacts clamped between the parts, and conducting members clamped between the parts and ex-

tending at right angles to the protruding contacts for electrically connecting opposite contacts together.

In witness whereof, I have hereunto subscribed my name in the presence of two witnesses. 15

HARRY W. DENHARD.
